TURBULENCE PRODUCING VALVE

August H. Wassman, St. Louis County, Mo., assignor to Carter Carburetor Corporation, St. Louis, Mo., a corporation of Delaware

Application November 28, 1942, Serial No. 467,210

2 Claims. (Cl. 261—41)

This invention relates to valves for controlling the supply of fluid through a pipe and particularly where the fluid includes a vapor, the fine atomization and even dispersion of which is desired. An example of this is found in carburetors for internal combustion engines where a mixture of air and liquid fuel vapor is drawn past the throttle valve into the engine intake manifold.

It is a continuation, in part, of my co-pending application, Serial No. 445,442, filed June 2, 1942.

In an automotive carburetor of the usual type, the throttle is formed by a plain butterfly type valve presenting a generally smooth surface to the passing vapors. Under low suction conditions in the carburetor, particularly when the throttle valve is substantially opened, the liquid fuel may be supplied in drops of substantial size which are not evenly dispersed in the intake manifold and result in uneven operation of the engine. The present invention has for its principal object the provision of a throttle valve of the above type which creates turbulence in the engine intake and substantially assists in the atomization and dispersion of the liquid fuel vapor.

In the drawings illustrating the invention:

Fig. 1 is a sectional view of a carburetor embodying the novel throttle valve.

Fig. 2 is a view of the novel valve somewhat enlarged so as to illustrate the formation of the vapor diverting ribs.

Fig. 3 is an edge view of the valve.

Fig. 4 is a top view of a modified valve.

Fig. 5 is a section on line 5—5 of Fig. 4.

Fig. 6 is a top view of a modified valve.

Fig. 7 is an edge view of the valve illustrated in Fig. 6.

Fig. 8 is a sectional view of the flange portion of a carburetor.

Fig. 9 is a top view of the throttle valve illustrated in Fig. 8.

Fig. 10 is an edge view of the valve illustrated in Fig. 9.

The carburetor shown in Fig. 1 is of the down-draft type having an induction conduit with an air inlet portion 1, mixing chamber 2, and outlet 3, there being main and primary venturis 4 just anterior to the mixing conduit. Air is supplied through the upper end of the conduit past a choker valve 5 and fuel is supplied through a main nozzle 6 from a fuel bowl 7 having the usual constant level mechanism. Idling fuel is supplied through jet tube 8 and passage 9 to port 10 adjacent the edge of the throttle when closed.

The discharge of fuel and air mixture is con-

trolled by the throttle valve plate 11 pivotally mounted on a shaft 12 in the outlet portion of the mixture conduit. The throttle plate is provided with a pair of outwardly projecting curved or pocketed baffles, as at 13 and 14, baffle 13 having a perforation 15. Baffles 13 and 14 are disposed so that the concave or pocketed sides thereof face against the direction of mixture flow when the throttle is tilted. The effect of these ribs is to catch and divert at least a portion of the fuel vapors passing the throttle, creating a turbulent condition which improves the atomization and dispersion of the mixture.

An auxiliary nozzle 16 extends into the mixture conduit adjacent venturis 4 for discharging accelerating fuel from a throttle operated pump 19 located, as usual, in bowl 7. Accelerating fuel is discharged against the anterior face of the throttle plate (Fig. 1) and hole 15 in diverting baffle 13 is provided to facilitate the passage of the accelerating charge to the engine. More than one of the holes may be provided, if desired.

In Figs. 4 and 5, the baffles 20 and 21 are provided with flanges 22 and 23 which may be secured beneath usual screws 24 for attaching the throttle plate 25 to its shaft 26.

I have found that the lower speeds; that is around 20 miles per hour when the effective suction applied to the main nozzle is relatively low so that fuel is supplied therefrom in droplets of substantial size, these are effectively atomized upon passing the throttle to form a visible mist. The novel turbulence producing throttle results in marked increase in economy, particularly, at the lower speeds and, in fact, permits the use of smaller fuel metering restrictions without adverse effect upon the performance of the engine, as would otherwise occur. The ribs may be permanently secured to or formed on the throttle plate, as in Fig. 2, or may be separately formed and attached as in Figs. 4 and 5. The carburetor fuel metering restrictions may be adjusted, as suggested, after the turbulence throttle is installed, but the novel valve will produce improved economy and smoother operation of the engine without other change.

In Figs. 6 and 7 the baffles 30 and 31 attached to the throttle plate 32 are somewhat similar to the pocketed baffles 13 and 14 of Figs. 2 and 3 but are constructed of perforated material such as fine mesh screen. By the use of screen baffles, the fuel mixture flowing through the induction conduit is agitated as it passes through the perforations and around the throttle valve. The use of screen baffles or ribs creates less restriction to

the fuel flow and facilitates the use of much higher baffles which, in turn, intercept a major portion of the fuel mixture passing the throttle valve.

The modification of the valve illustrated in Figs. 8, 9 and 10 differ from the preceding modifications in that the baffles 35 and 36 are identically positioned on the throttle valve 37. Baffles 35 and 36 are spherically shaped and set inwardly from the edge of throttle valve 37 so that they maintain a spaced relationship to the walls of the mixture conduit during the opening movement of the throttle valve, as indicated by the broken lines 38.

Throttle plate 37 assumes the position shown in Fig. 8 during idling and the fuel mixture issuing from idle port 38 passes through the perforated baffle 36 and is more thoroughly atomized. During the opening movement of the throttle valve, baffle 36 maintains its spaced relationship to the idle port and intercepts the fuel mixture from the idle port throughout the part throttle range.

Baffle 35, having its pocket facing against the normal flow of air through the conduit, is so positioned as to catch the discharge from an auxiliary nozzle discharging accelerating fuel as previously described. Some of the accelerating fuel may flow in a liquid state through the perforated baffle 35 to the edge of the throttle plate before being picked up by the air stream flowing past the throttle valve while part of the liquid fuel is picked up by the air stream and thoroughly atomized as it passes through the perforated baffle and around the throttle plate.

The baffles 35 and 36 being so positioned, expose a greater baffle area to the mixture flow at

wide open throttle position and a greater turbulence and more complete atomization of the fuel mixture is achieved.

The shaping and arrangement of the turbulence producing ribs may be modified such as by providing flat or non-perforated ribs and the exclusive use of all such modifications as come within the scope of the appended claims is contemplated.

10 I claim:

15 1. In a carburetor, an induction conduit, a butterfly throttle pivoted therein, an idle port discharging into said conduit adjacent an edge of said throttle when closed, and a baffle screen attached to said throttle valve side adjacent said port and projecting in the direction of closing movement of said edge relative to said port as to intercept and atomize the fuel emerging from said port throughout the part throttle range of said throttle valve.

20 2. In a carburetor, a downdraft induction conduit, a throttle disc pivoted therein, an accelerating nozzle discharging into said conduit above said throttle valve, an idle port discharging into said conduit adjacent an edge of said throttle valve when closed, said edge moving anteriorly relative to said port during the throttle opening movement, a foraminous baffle projecting posteriorly from said throttle edge for intercepting and atomizing the fuel discharged from said port in the part throttle range of said throttle valve, and a second foraminous baffle projecting anteriorly from the opposite edge of said throttle valve for intercepting and atomizing the discharge from said pump.

AUGUST H. WASSMAN.
